UNITED STATES PATENT OFFICE.

JAMES A. DORAN AND JOSEPH G. DORAN, OF PROVIDENCE, RHODE ISLAND.

SEPARABLE BUTTON.

1,337,889.

Specification of Letters Patent. Patented Apr. 20, 1920.

Application filed October 13, 1919. Serial No. 330,242.

To all whom it may concern:

Be it known that we, JAMES A. DORAN and JOSEPH G. DORAN, citizens of the United States, residing at Providence, in the county 5 of Providence and State of Rhode Island, have invented a certain new and useful Improvement in Separable Buttons, of which the following is a full, clear, and exact description.

This invention relates primarily to that 10 type of separable buttons which are used for fastening together soft or French cuffs and quite commonly called link cuff buttons, wherein the button parts or members remain in the button-holes when said parts are separated in order to open or unfasten the cuffs.

The objects of the invention are to 15 strengthen the construction, conceal one of the connecting flanges and thereby improve the appearance as well as to stiffen the connection, in fact eliminate undesirable flexibility, and generally to better the structural and operative details and the finish of the article.

The invention consists of a separable 20 so-called link cuff button, the bodies of the socket and head members of which are made with integral posts or shanks and these posts or shanks provided with end 25 flanges or shoes of such construction that one of them may be concealed within the other when the parts of the button are connected or snapped together, so that instead of both flanges being exposed when the parts are so 30 connected, only one flange is exposed, as we 35 will proceed now to explain and finally claim.

In the accompanying drawings illustrating 40 the invention, in the several figures of which like parts are similarly designated, Figure 1 is a half section and elevation of the snapped-together parts. Fig. 2 is a section of the socket member and Fig. 3 is a section of the head member separated. Fig. 4 is a section of the blank from which the 45 head member of the button is formed. Fig. 5 is a section showing a modification of the means for securing the ornamental face to either member of the button. Fig. 6 is a 50 section showing a modification of the socket member. Fig. 7 is a section showing another modification of the socket member. Fig. 8 is a perspective view of the blank for the body of the socket member, and Fig. 55 9 is a perspective view of this element hav-

ing its split post spread to form the flange or shoe. Fig. 10 is a plan view of one form of socket spring, and Fig. 11 is a plan view of another form of socket spring.

As already indicated, separable buttons 60 for use on soft or French cuffs are well known. In some of them the socket member and the head member have posts or shanks which terminate at their connecting ends in flanges and a swinging or equivalent connecting medium is interposed whereby the members may be separably connected so as to join the ends of the cuff. In these buttons as in ours the two adjacent flanges or 65 shoes are necessary or desirable for coöperation with the outer heads or flanges to retain the members in the buttonholes when the button is separated but when both are exposed they produce a clumsy and unsightly appearance. In our invention we 70 use the two flanges or shoes but conceal one within the other when in use, and the connection is substantially rigid, so that there can be no swinging movement of the connection itself, and this condition is enhanced 75 by the socketing of one flange within the other, the spring in the socket member tending to draw the head and flange of the head member into such intimate contact with the socket member as to preclude any swinging 80 movement, as will appear from the following explanation.

The socket member as shown in Figs. 1 and 2 comprises a cup 1 made with the rim flange 2, and the post or shank 3 having the 85 flanged end 4, all of these parts preferably being integral and drawn to shape. The flanged cup is closed in upon any suitable ornamental face piece 5. The flanged post is provided with a collet 6 having its rim 90 closed over the flanged end 4 as at 7. A spring 8, such as shown in Fig. 10 or Fig. 11 is placed next to the flanged end and within the closed-in rim of the collet so as to center it, and then the cup-shaped back 95 9 is applied to the thus assembled parts and its rim 10 closed in over the collet 6. A hole 11 is made in the back so as to expose the gripping portions of the spring 8 for engagement with the head. The flanged 100 end of the post, the collet and the back constitute what is herein referred to as the socket member flange or shoe.

The head, as shown in Figs. 1 and 3, comprises a cup 12 having a rim 13 which is 105

adapted to be closed in upon an ornament 13', and a post or shank 14 to which is rigidly secured the flange 15, herein shown as a cup of a size and conformation adapted 5 to receive and conceal the flange of the socket member. The head blank, Fig. 4, shows the post 14 as made of two diameters so as to provide a shoulder 16 to receive and support the flange 15, and when the said flange is so 10 positioned the smaller portion of the post is upset or collapsed above the flange to form the collar 17, Fig. 3, which engages the flange and binds it rigidly to the shoulder; the remainder of the post being shaped to 15 form the spring-engaging head 18. In the preferred construction the flange 15 has a countersunk portion 19 to receive the collar 17 and so present a level surface in the bottom of the flange 15 to correspond to and 20 coact with the level face of the flange of the socket member.

The construction of socket and head members of a separable fastener or button thus described provides a rigid and fixed head or 25 connecting medium (18) for the union of the socket and head members in a substantially rigid manner. When the socket flange is inserted in the flange of the head member as in Fig. 1, and the head 18 is engaging the 30 spring of the socket member, the laterally extending bottoms of both flanges are in intimate extensive contact with one another so that any undesirable swinging or tilting movement is prevented; and moreover, the 35 flange of the socket member is wholly concealed within the flange of the head member, so that instead of there being two exposed adjacent flanges tending to render the appearance of the button clumsy and inartistic, 40 our button presents a symmetrical and pleasing appearance.

In addition to the advantages already pointed out, there is a further advantage in the decrease in cost of material and labor 45 in our construction as compared with others.

As shown in Fig. 5, the outer end of both socket and head members or either of them may be plain disks 20, and a separate flanged ring 21 may be closed down upon the flange 50 or ornament to unite them.

As shown in Fig. 6, the collet of Figs. 1 and 2 may be omitted and instead thereof may be used the inverted cupped washer 22 which incloses the spring and positions the 55 back 9 relatively thereto, the rim of the back being closed down over the flanged end 4 of the post.

As shown in Fig. 7, the construction illustrated in Fig. 6 may be provided with a finishing washer 23 which may be laid over the flange 4 and the back closed down upon it.

As shown in Figs. 8 and 9, the post 3 is slotted longitudinally at 24 and then in order to form the flange 4, the slotted portions are 65 turned out at right angles to the post so as

to form lateral extensions which constitute the flange 4. This construction is adopted because of its adaptability to integrality of construction and consequent strength in the article and economy of its production.

Fig. 10 shows one form of spring that may be used in the socket member, the same being of ring form with its ends 25 turned in in parallel relation to engage the head 18. As shown in Fig. 11, the spring may be made 75 somewhat stiffer by doubling its ends as at 26. These and other forms of springs common to snap fasteners and other forms of separable buttons may be used in the construction of the socket member.

It will be understood that the button is used by passing the flanges or shoes of its respective members through opposite button-holes in the cuff to be fastened or linked, and then the flange of the socket member is inserted in the cup-like flange of the head member and the head 18 of the head member is then forced into engagement with the spring in the socket member and the parts thus securely united or connected. As already stated, when the socket member and the head member of the button are thus assembled, only one connecting flange appears and thus the symmetry of the button is improved; and not only is there this improvement in appearance, but the connection is more secure since there is no chance for an obstacle to come in between the flanges of the two members and tend to separate them.

In our construction the post or shank and the cupped flange or base of the socket member and the head member are in one piece, whereby great strength is attained at a point which bears heavy strains. The active head portion 18 is also in one piece with its post 105 or shank; which construction likewise gives great strength, prevents breakage, and reduces the cost of manufacturing, while securing the desired rigidity or inflexibility. The nesting of the intermediate flanges or 110 shoes one within the other insures two flat contact surfaces pressing together and thereby controlling or preventing side play or looseness, in addition to furnishing a finished product of superior appearance over 115 those buttons in which corresponding parts are both exposed.

It will be understood that in the various constructions herein shown and described, the spring is so arranged and supported as 120 to have perfect freedom of vibration without chance of displacement.

The several one-piece parts of the button members may be formed by any usual or approved drawing process.

The invention is not limited to the contour or configuration of the ornamental ends of the button, nor to the manner of finishing these ends, nor to the kind or nature of the ornament used. These and other variations 130

are deemed to be within the principle of the invention as herein explained and hereinafter claimed.

What we claim is:—

- 5 1. A separable button, having a socket member and a complemental head member, said members having adjacent flanges or shoes, one of which is concealed within the other, and means to separably connect said
- 10 members consisting of a spring element and a coöperating rigid and inflexible head adapted to engage with said spring element.
- 15 2. A separable button, having a socket member and a complemental head member, said members having adjacent flanges or shoes, one of which is concealed within the other, the socket member having a resilient fastening element and the head member having a rigid and inflexible head element
- 20 coöperating with said resilient element to separably connect the socket and head members.
- 25 3. A separable button, having socket and head members each composed of a cupped end and post made of one piece, and flanges on the ends of the respective posts adapted to fit one within the other, and complemental engaging means carried in said flanges to effect a separable connection of the socket
- 30 and head members independently of the flanges.
- 35 4. In a separable button, a socket member having a flanged cup and a post projecting therefrom and terminating in a laterally extending flange, said cap, post and flange formed in one integral piece, a spring applied to the post and resting upon its flange, and a back closed in over the spring and the laterally extending flange.
- 40 5. In a separable button, a socket member having a flanged cup and a post projecting

therefrom and terminating in a laterally extending flange, a spring applied to the post, a collet applied to the flange and circumscribing the spring, and a back closed in 45 over the spring and collet.

6. In a separable button, a head member having a flanged cup and a post formed as a rigid part thereof and projecting therefrom and made in different diameters, the 50 larger diameter having a shoulder, and a cupped flange resting upon said shoulder and rigidly held in place thereon by means of a collar formed on the smaller diameter of the post, said post terminating in a socket- 55 engaging head.

7. In a separable button, a head member having a flanged cup and a post rigid therewith and projecting therefrom and made in different diameters, the larger diameter hav- 60 ing a shoulder, and a cupped flange having a countersunk portion resting on said shoulder, the smaller diameter of the post being upset within said countersunk portion to rigidly fix the flange on the post, and said 65 post terminating in a socket engaging head.

8. In a separable button, a head member having a flanged cup and a post formed as a rigid part thereof and projecting therefrom and made in different diameters, the larger 70 diameter having a shoulder, and a cupped flange resting upon said shoulder and rigidly held in place thereon by means of a fixed collar on the smaller diameter of the post, said post terminating in a socket-engaging 75 head made rigid therewith.

In testimony whereof we have hereunto set our hands this 10th day of October, A. D. 1919.

JAMES A. DORAN.
JOSEPH G. DORAN.
